UNITED STATES PATENT OFFICE.

JAMES E. MOLONY, OF SCHENECTADY, NEW YORK, ASSIGNOR TO GENERAL ELECTRIC COMPANY, A CORPORATION OF NEW YORK.

AUTOMATIC SECTIONALIZING-SWITCH.

1,103,605.

Specification of Letters Patent. Patented Aug. 25, 1914.

Application filed September 11, 1909. Serial No. 517,278.

To all whom it may concern:

Be it known that I, JAMES E. MOLONY, a citizen of the United States, residing at Schenectady, county of Schenectady, State of New York, have invented certain new and useful Improvements in Automatic Sectionalizing-Switches, of which the following is a specification.

This invention relates to systems of electrical distribution and especially to sectionalized systems provided with automatic switches for connecting and disconnecting the sections. A system of this character is disclosed in Patent No. 916,988, granted April 6, 1909, to Walter S. Bralley. In that patent, the solenoid coil which closes the main switch connecting the sections of the conductor remains constantly in circuit so long as the switch is closed.

The object of my invention is to prevent the loss of current consumed by this large coil, and also to provide for opening the switch when a failure of current occurs.

In carrying out my invention, I take advantage of a form of automatic switch shown in the patent to S. B. Stewart, No. 832,703, granted October 9, 1906, which I have modified to make it perform the functions of a sectionalizing switch, by causing its actuating coil to open its own circuit after closing the switch lever, and by utilizing the auxiliary manual-control tripping coil of said patent as an automatic closing coil and also as a no-voltage release coil.

The accompanying drawing is a diagram representing my invention.

The two adjacent sections 1 and 2 of a sectionalized conductor are shown as supplied with current through their respective feeders 3, 4. A contact-arm 5 is pivotally supported at one end by the pivot 6, and this end of said arm is permanently connected by the branch wire 7 with the section 1 of the conductor. The overload coil 8 is included in this branch. The free end of the arm is provided with a brush-contact 9 and an auxiliary shunt-contact 10 which are adapted to cooperate with a fixed contact 11. A branch wire 12, including the blow-out coil 13, connects said fixed contact with the section 2 of the conductor. The arm and its contacts normally tend to open by their own weight, assisted, if need be, by a coiled spring 14 attached at one end 56 to said arm and at the other to some sta-

tionary support. In order to close the contacts 9 and 10 upon the contact 11, the movable core 15 of a solenoid 16 is pivoted to the contact-arm at 17. One end of the solenoid winding is grounded at 18, and the other end is connected by the wire 19 with the section 1, preferably through the branch wire 7, as shown. There are two interlocks in this wire 19, one of which is the floating contact 20 carried loosely on a stem 21 rising from the core 15, and having a certain amount of lost motion between the collars 22 on said stem. The other interlock comprises a contact 23 actuated by a coil 24 in a circuit 25 connected at one end with the section 2 through a hand switch 26, and grounded at the other end through a resistance 27.

When the main switch is once closed through the energization of the coil 16, it is held in closed position by a toggle comprising the links 28 and 29, acting between the contact-arm 5 and a fixed pivot 30. This toggle is not overset when holding the switch closed, but is kept from collapsing by means of a pivot-latch 31, which engages an overhanging portion 32 of the link 28 of the toggle. The latch is, in fact, a lever pivoted upon the pivot 30. The free end of this lever extends into the path of movement of the armature 33 of the overload coil 8. Springs 34 and 35 are respectively connected to the latch and the armature. Upon the occurrence of an overload, the armature 33 is drawn upward against the tension of the spring 35 into engagement with the free end of the latch, which it lifts and thereby releases the toggle and allows it to collapse under the weight of the contact-arm, assisted by the spring 14, thus opening the switch. This position of the parts is shown in the drawing. Furthermore, in order that the switch may open on a lowering or a failure of voltage, the core of the solenoid 24 is arranged to drop upon a lever 36 whose other end lies under the armature 33. When the circuit 25 is closed, a spring 37 pulls the lever 36 down and away from the armature, but when the switch 26 is opened, or in case of a failure of voltage when said switch is closed, the core of the solenoid 24 drops and by throwing up the lever 36, trips the toggle and opens the main switch.

My invention thus provides for an auto-

matic opening of the sectionalizing switch either in case of a ground on either section causing a rush of current sufficient to energize the overload coil 8, or on the other hand 5 in case of a failure of voltage deenergizing the no-voltage coil 24. The sectionalizing switch will be automatically closed upon the closing of the hand switch 26, if both sections 1 and 2 are energized. The current 10 flows through the switch 26 and the no-voltage coil 24 and resistance 27 to ground, picking up the interlock 23. This closes the circuit of the main actuating coil 16, which closes the main switch and connects the two 15 sections 1 and 2. When the contact-arm 5 closes, the interlock 20 will be opened at the same instant, breaking the circuit of the coil 16, but inasmuch as the catch levers have also at this time become engaged, the switch 20 will remain closed.

The chief advantage of my invention is that the current required to operate it is inconsiderable. The only coil in circuit consuming extra current after the switch has 25 closed is the small no-voltage coil 24, and the current through this is reduced to a minimum by the resistance 27.

What I claim as new and desire to secure by Letters Patent of the United States, is:—
30 1. The combination with two sections of an electrical conductor each having its own feeder, of an automatic connecting switch comprising an electromagnet, a contact arm actuated thereby, and two interlocks controlling the circuit of said electromagnet, one 35 opened by the electromagnet when it is energized, and the other controlled by a no-voltage coil connected with one of said sections.

2. The combination with two sections of 40 an electrical conductor each having its own

feeder, of an automatic connecting switch comprising an electromagnet, a contact-arm actuated thereby, a mechanical lock for holding said arm closed, an overload coil adapted to trip said lock, and two interlocks controlling the circuit of said electromagnet, one adapted to be opened by the electromagnet when energized, and the other controlled by a no-voltage coil connected to one of said sections. 45

3. The combination with two sections of an electrical conductor each having its own feeder, of an automatic connecting switch comprising an electromagnet, a contact-arm actuated thereby, a toggle and catch for locking said arm when closed, an overload coil adapted to trip said toggle, a no-voltage coil also adapted to trip said toggle, and two interlocks in circuit with said electromagnet, one controlled by said electromagnet, and 50 the other by said no-voltage coil. 55

4. An electric switching device for connecting two sections of an electric conductor comprising, a switch for electrically connecting said sections, a locking toggle for holding said switch in a closed position, an overload coil, an armature coöperating with said overload coil to release said locking toggle and open said switch on appearance of overload, a lever coöperating with said armature, 65 and a no-voltage coil acting directly upon said lever to independently release said locking toggle and open said switch on appearance of an abnormally low voltage. 70

In witness whereof, I have hereunto set my hand this 9th day of September, 1909.

JAMES E. MOLONY.
